UNITED STATES PATENT OFFICE.

FERDINAND LALLEMAND, OF MARSEILLE, FRANCE.

MOVABLE DEFLECTOR FOR FLUID STREAMS.

Application filed April 10, 1924, Serial No. 705,474, and in France April 12, 1923.

My invention relates to movable deflectors for fluid streams produced by known means in which the stream of fluid is deflected in a direction which is instantaneously variable, and the aim is:

1. To obtain by means of the proposed deflector the deviation of a constantly flowing current of permanent character and the production of an irregular, or even, interrupted flow of whirls as required, the deflecting surfaces being driven in their relative movements exclusively by the air current.
2. To obtain different modes of variation of the wind direction; i. e. alternative deviation, towards the right or the left in the same plane, or otherwise according to the surface of a cone, or otherwise a continually rotating deviation along the generatrix of a cone the vertex of which is constituted by the deflector centre, always without the need of a mechanical driving connection between the ventilator or fan driving shaft and the axes of the deflecting surfaces.
3. To obtain the direction variations more or less rapidly.

I attain these aims by means of the mechanism illustrated in the accompanying drawings, in which,

Fig. 1 shows in side view and in connection with known household electric fans or ventilators a deflector performing alternative deviations with two deflecting blades or wings acting upon an horizontal air current. The pivotal axis of the deflector is above the wings.

Fig. 2 is a front view of the device illustrated in Fig. 1.

Fig. 3 shows in front view a deflector for alternative deviations with two blades or wings in which the axis is disposed below the centre of the wings.

Fig. 4 is a front view of a deflector provided with three blades in which the axis roughly coincides with the centre of the figure.

Fig. 5 is a sectional view of a deflector with several blades, the movable oscillating frame of which is connected by rods with two parallel axes and in which the movement of the frame is limited by abutments.

Fig. 6 is a perpendicular sectional view with reference to the axis of a wing.

Fig. 7 is a front view of the rotating deflecting wings in another form of execution.

Fig. 8 is a side view of the device shown in Fig. 7.

Similar reference characters refer to similar parts throughout the drawings.

I dispose in the air or other fluid current one or more blades preferably parallel and of an elongated shape and receiving the impulse of the wind along the larger side.

The whole of the wings forms a sort of shutter the elements of which are each adapted to rotate upon an axis approximately perpendicular to the general direction of the wind. A particular case shall be described further on in connection with Fig. 4.

The wing axes are parallel to each other and turn as a whole about an axis approximately parallel to the general direction of the wind. Each wing axis is nearer to the wind receiving edge preferably at about one-third of the wing width counting from the wind receiving edge.

The wings are pivotally mounted on their axes to allow them to assume predetermined positions due to the combined action of the fluid inertia and gravity. The wings are interconnected by means of rods.

For each element or wing the inclination of same with reference to the general direction of the fluid flow is uniform or at least in the same sense from end to end.

The section of the wing between the edge receiving the wind and the exit edge may be rectilineal or curved, thin or thick without interfering with the working of the device. I prefer to use wings with a thick convex section so that the axis passes at the interior.

Variations of deflection in working, speed and direction may be obtained, changing the combination of the elements according to the direction of the wind which may be horizontal or inclined at any angles, viz:

1. The position of the axis supporting the movable frame with reference to the whole of the surfaces receiving the wind impulsion.
2. The weight of the movable portion and the position of its centre of gravity at a distance from the axis.
3. The weight of the wing and the position of its own centre of gravity between the wind receiving edge and its axis or on the axis, or otherwise between the wing axis and the wind exit edge.

4. The position of the wing axis with reference to the wind receiving edge, more or less at a distance but always in the portion nearer to this edge.
5. The mode of changing the orientation of the wings at the end of each stroke, either by means of the mere action of gravity on the movable wings, when the wind direction is sensibly horizontal; or otherwise
- 10 by means of stops acting either on the carrying framing of the movable wings, or on the wings directly.

In Figs. 1 and 2 the deflector is shown with a sustaining foot connected to the external casing of a known electric fan. This foot may be fixed in any suitable place, such as the base of the ventilator casing or on the protecting cage or otherwise independently of the fan. The said supporting foot

15 is terminated by a cylindrical portion A serving as an axis for the movable frame, the latter being held in position by known means.

This axis is approximately in the same direction as the main initial wind direction.

B, B are the blades, mounted on the movable framing C and the arms D, D serve as axes. The rods E, E are the interconnecting means. The framing C carries a bush F

30 engaging upon the member A.

In this apparatus intended for approximately horizontal fluid current in which the axis A is above the centre of pressure on the wings, the centre of gravity of the wings should be between the wind receiving edge and their axis.

An alternating deviation is thus obtained sweeping in each direction a portion of a cone surface.

40 In Fig. 3 in which the deflector axis for horizontal currents is disposed below the centre of pressure on the wings, the centre of gravity of the latter falls between their axes D and the fluid exit edge.

45 A counterweight or equivalent keeps the rocking movement of the frame about its axis within the desired angle.

In the form shown in Fig. 4, when the axis is in proximity to the geometric centre 50 of the wing configuration or coincides with it, and the whole is indifferently balanced, the device, placed before a fan, rotates and always in the same sense. According to the position of the centre of gravity G of each 55 wing between the wing axis and the wind receiving edge, or between the axis and the wind exit edge, the deviation happens in different directions.

More particularly when G is on the axis 60 of the wing the latter does not move and a uniform turning deflection is realized.

In this case the wing axis is useless and I prefer to fix the wings with reference to the framing C (Figs. 7 and 8).

65 I adjust the incidence angle on the wind

and give the wings a curved shape giving to the wind a progressive deflection without shocks.

To obtain the desired speed I adjust the inclination accordingly, varying it from end to end in the whole length of one or more wings or displacing the wings as a whole with reference to the axis A, always keeping the whole system indifferently balanced.

75 The movable framing, instead of moving round an axis, may be guided in any known way (Fig. 5) provided that in this displacement the wing axis remains always approximately perpendicular to the wind direction; i. e. in Fig. 5 the framing O is connected by two rods 1, 1 to two parallel axes; the stroke is limited by the stops J, J working here in proximity of the wind receiving edge and the deflection happens permanently in the same plane.

These devices serve for:

Household mechanically driven fans, ventilation in general flowing fluid mixing plants without external motive power; as a wind disperser for vehicles; production of motive power (preferably with alternating deflectors); volume or speed measuring apparatus for moving fluids, advertising devices and toys.

I am aware that previous to my invention air current deflectors have been used and I do not claim the deflectors broadly.

What I claim is:

1. Deflectors for fluid currents comprising a plurality of deflecting wings moved exclusively by the fluid current having each an axis which is approximately perpendicular to the direction of the current, the axis of each wing being placed nearer the fluid receiving edge of the wing the angle of inclination being throughout in the same sense along the length of the wing.

2. Deflectors for fluid streams moved exclusively by the fluid stream comprising a movable frame and a series of movable wings carried thereby, the said wings constantly moving about their axes, and the frame moving about an axis which remains approximately parallel to the direction of the wind.

3. Deflectors for fluid streams moved exclusively by the fluid stream, comprising constantly moving pivoted deflecting surfaces which take positions predetermined by the combination of the gravity inertia and the action of the current on the wings.

4. Deflectors for fluid streams moved exclusively by the fluid stream, comprising a constantly moving frame, deflecting blades inclined, with reference to the wind direction, in the same sense throughout their length, said blades being adjustably fixed on the constantly moving frame, wings and frame as a whole being indifferently balanced with reference to an axis the direction

of which is approximately parallel to the wind direction; the frame moving at a speed determined by the difference of inclination of the wings along their length.

5. Deflectors for fluid streams moved exclusively by the fluid stream, comprising a rotatable framing, and a plurality of approximately parallelly disposed inclined

wings, and fixed to the framing, the axis of rotation being displaced with reference ¹⁰ to the center of said plurality of wings so as to obtain the required speed of revolution.

In testimony whereof I have signed my name to this specification.

FERDINAND LALLEMAND.
